UNITED STATES PATENT OFFICE.

GEORGE WILSHEAR BULLEY, OF ST. JOSEPH, MICHIGAN.

DESIGN FOR A RUBBER HEEL.

57,032.

Specification for Design.

Patented Feb. 1, 1921.

Application filed June 5, 1919. Serial No. 302,076. Term of patent 14 years.

To all whom it may concern:

Be it known that I, GEORGE W. BULLEY, a citizen of the United States, residing at St. Joseph, Michigan, have invented a new, original, and ornamental Design for Rubber Heels, of which the following is a specification, reference being had to the accompanying drawing.

In this drawing Figures 1 and 2 are plan

views of opposite faces respectively of a heel showing my new design, Fig. 3 is a longitudinal cross section and Fig. 4 a transverse cross section.

I claim—

The ornamental design for a rubber heel as shown.

In testimony whereof I affix my signature.
GEORGE WILSHEAR BULLEY.
